UNITED STATES PATENT OFFICE

164,628

COVER FOR CONTAINERS FOR PERISHABLE FOODS

Calvin Davis, Salinas, Calif.

Application May 26, 1950, Serial No. 10,214

Term of patent 14 years

(Cl. D58—12.6)

To all whom it may concern:

Be it known that I, Calvin Davis, a citizen of the United States, residing at Salinas, Monterey County, State of California, have invented a new, original, and ornamental Design for a Cover for Containers for Perishable Foods, of which the following is the specification, reference being had to the accompanying drawing, forming a part hereof.

I claim:

The ornamental design for a cover for containers for perishable foods, as shown.

CALVIN DAVIS.
